MECHANISM FOR TYPESETTING MACHINES

Filed Oct. 31, 1929

Fig. 2.

Inventor:

James W. Phelps
by George A. Rockwell,
Atty.

UNITED STATES PATENT OFFICE

JAMES W. PHELPS, OF MELROSE, MASSACHUSETTS, ASSIGNOR TO STOWE & WOODWARD COMPANY, OF NEWTON UPPER FALLS, MASSACHUSETTS, A CORPORATION OF MASSACHUSETTS

MECHANISM FOR TYPESETTING MACHINES

Application filed October 31, 1929. Serial No. 403,679.

The principal object of my invention is to improve the construction and operation of the member commonly called a star wheel, which advances the elements, such as matrices and space bands, to the assembling point.

A feature of my invention is the forming of said member with a shelf to receive one of the elements referred to and with a projection or tooth curved at its outer end, to draw the matrix or space band from said shelf into assembling position with a wiping or rolling motion instead instead of a striking motion.

Another feature is the arrangement of said shelf at a relatively low point, preferably somewhat below the axis of the star wheel, one object of this being to lower said elements, and especially the space bands, into position without jar.

Another feature is that I make my advancing member or star wheel of rubber, preferably medium hard, with a plastometer reading of about $20\frac{1}{8}$ P.

Other features will be pointed out below.

In the drawing

Figure 1 is an elevation of a portion of a typesetting machine embodying my invention; and

Figure 2 is a detail in elevation on a slightly larger scale showing the mounting of the star wheel.

Upon the carriage 1 is mounted the slide finger 2 and the adjusting screw 3, the member 4 being provided to guide the matrices from the belt 5 to the star wheel or element 6 which advances the matrices to the assembling point, all of this, except my member 6, being well known in the art.

The member 6 is mounted on shaft 7 to which is fixed a friction disk 8. Pinion 9 is operated by suitable gearing (not shown) and fits over the disk 8 but is not supported by the shaft 7. A portion 10 is mounted on the end of the shaft and is one abutment for the spring 11, whose other abutment is pinion

9 so that, in the case of an overset matrix line the star wheel will stop, the spring permitting the pinion 9 to continue revolving by slipping against the disk 8, which with the

wheel 6 is then temporarily held stationary, all of which, except wheel 6, being well known in this art and being substantially disclosed in U. S. Letters Patent to Goodbody No. 1,657,962 dated January 31, 1928.

The space bands may be fed through a chute, not necessary to be shown in the drawing, which is to be located directly above the star wheel, whose shelves receive the space bands.

Star wheel 6 rotates in the direction of the arrow in Figure 1 and has four projections each having an outer end curved at 12 and having a shelf 13 upon which the lower end of each matrix 14 rests, the shelf being substantially parallel with the end of the matrix when the latter engages the shelf. The four projections are off centre, any shelf, when in horizontal left-hand position, being lower than the horizontal plane through the axis of the star wheel.

A feature of my invention is that my star wheel is made of rubber, preferably medium hard rubber with a plastometer of about $20\frac{1}{8}$ P. Among the advantages of this material I may point out that with rubber there is no likelihood of the matrix or space band bounding out from the star wheel as the shelves are not too hard. Moreover the feeding to the assembling point will not be too hard and the rubber will have a much longer life than the life of the star wheel heretofore used and the matrices and space bands will last longer.

In using my wheel the shelf of one projection and the curved outer portion of the next following projection cooperate as the wheel rotates to impart a rolling or wiping motion which advances the matrices to assembly position without striking them, the curved portion wiping the matrix from the shelf. The position of the shelves is such that they receive the space bands at a much lower point than heretofore and thus lower the space band to position without jar and by a wiping motion.

What I claim is:

1. A device of the character described comprising a rotary member to advance elements to a desired point and having a shelf, the

plane of which, when the shelf is in horizontal operative position, is substantially lower than the horizontal plane through the axis of said rotary member, the latter being provided 5 with a portion to remove said elements from said shelf; and means to rotate said member.

2. A device of the character described comprising a rotary member to advance elements to a desired point and having a shelf, the 10 plane of which, when the shelf is in horizontal operative position, is substantially lower than the horizontal plane through the axis of said rotary member, the latter having a projection curved at its outer end, said curved 15 portion acting to remove said elements from said shelf; and means to rotate said member.

3. As an article of manufacture for typesetting machines a member to be rotated to advance matrices or space bands, said member having a shelf the plane of which, when the shelf is in horizontal operative position, is substantially lower than the horizontal plane through the axis of said member, the latter being provided with a portion located to remove the matrices or space bands from said shelf. 25

4. As an article of manufacture for typesetting machines a member to be rotated to advance matrices or space bands, said member being made of rubber and having a shelf, the plane of which, when the shelf is in horizontal operative position, is substantially lower than the horizontal plane through the axis of said member, the latter having a projection curved at its outer end and located to remove the matrices or space bands from said shelf. 35

JAMES W. PHELPS.
